UNITED STATES PATENT OFFICE.

ROBERT C. HYDE, OF DES MOINES, IOWA.

ANNULAR EXHAUST TIP.

Application filed October 11, 1926. Serial No. 140,838.

The object of this invention is to provide an improved exhaust tip for locomotive exhaust nozzles, so constructed and arranged as to decrease the retarding influence on the 5 exhaust steam as it passes to the stack, thus perfectly sealing the stack at its base and increasing the pull over the entire fire box area, permitting the opening of the nozzle tip to be enlarged, which reduces the back 10 pressure as well as decreases the compression in the cylinder, reducing the wear on moving parts and decreasing the fuel consumption.

A further object is to provide an exhaust 15 tip including a tapered bushing mounted in the tip to supply a perfect annular sheet of steam at the base of the stack.

With these and other objects in view, my invention consists in the construction, 20 arrangement and combination of elements hereinafter set forth, pointed out in the claims and illustrated by the accompanying drawing, in which—

Figure 1 is a vertical section of my im- 25 proved nozzle tip, taken on the line 1—1 of Figure 2.

Figure 2 is a plan view of the tip in as- 30 sembled form.

Figure 3 is a perspective view of the 35 tapered bushing removed from the tip.

Figure 4 is a vertical section showing the 40 tip mounted in position for use in the smoke box of a locomotive.

In the construction of the device as shown 45 the numeral 10 designates an exhaust nozzle which is mounted in the smoke box 11 of a locomotive or the like engine, immediately below the stack 12, to which it is adapted to discharge a stream of exhaust 50 steam received through the passages 13 from the cylinders, in a common manner, for the purpose of creating a draft through the stack.

My invention relates to the tip for the 55 exhaust nozzle 10, the body 14 of which is of substantially cylindrical form and suitably secured to the nozzle. Mounted within the tip body 14 is a tubular bushing 15, open at both ends, of less diameter and length than said tip body and supported in the upper end thereof so that their upper ends are substantially flush. The lower portion of the wall of the tip body 10 is flared or tapered so as to produce a bore of sub- 60 stantially truncated conical form, as indicated at 16, and the lower end of the bush-

ing 15 also is tapered or beveled away from the wall of the tip body, thus increasing the upward taper of the annular passage formed between the lower walls of the said 60 members. The upper portion of this annular passage may be substantially cylindrical. The bushing 15 is formed with a plurality of spaced wings, in this instance four in number and designated by the numerals 17, 65 which wings are integrally formed on its outer surface, extend down approximately half way of the length of the bushing, and bridge the space between it and the wall of the tip 14. The wings 17 preferably are 70 tapered at their lower ends to decrease resistance on the passing steam, and are formed at their upper ends with notches 18 arranged radially of the bushing and extending through the upper wall thereof. The 75 outer edges of the wings 17 are designed to have a tight fit within the wall of the tip 14 to hold the bushing in place, but I have also shown other means for holding the bushing in place, comprising lugs 19 80 fitted tightly within the grooves 18 and extended to overlapping relation with the upper margin of the tip 14, to which they are secured by screws 20.

It will be noted that by mounting the 85 tapered bushing in the nozzle tip, there is very little obstruction which would result in retardation of the exhaust steam, and also that an annular sheet of steam is projected from the tip to the base of the 90 stack 12, forming a perfect seal at the base of the stack and increasing the pull over the entire fire box area. This arrangement permits the opening of the tip to be enlarged materially, thus reducing the back 95 pressure as well as decreasing the compression in the cylinders, and tending to reduce wear on the moving parts therein because of the increased area of the tip. The tapering of the bushing and the wall of the tip 100 body at 16, thus producing an annular passage of substantially conical section, results in a lessening of the retarding effect on the exhaust steam. This arrangement has resulted in a material saving of fuel consumption ranging from about ten to six- 105 teen per cent.

The form of nozzle and tip may of course be varied from that here shown and de- 110 scribed for purposes of illustrating my improvement, and it will be understood that my invention is adapted for use with other

types of nozzle tips without departing from the spirit of my invention.

I claim as my invention—

1. An exhaust nozzle tip comprising a substantially cylindrical body and a tubular bushing open at both ends and of less diameter than said body and mounted therein, whereby an annular passage is provided between said body and bushing, said bushing being tapered uniformly from its upper to its lower end.
2. An exhaust nozzle tip comprising a substantially cylindrical body and a tubular bushing open at both ends and of less length and diameter than said body and arranged in the upper end thereof, said bushing be-

ing formed with relatively narrow wings on its outer face extending into engagement with the inner wall of the body, and lugs carried by said wings and overlying the upper margin of the body.

3. An exhaust nozzle tip comprising a substantially cylindrical body, a tubular bushing open at both ends mounted concentrically within said body, and means for securing said bushing rigidly in place, the wall of said bushing being tapered in thickness toward its lower end and the inner wall of the body sloping away from such tapered portion.

ROBERT C. HYDE.
